(57) **CLAIM**

The ornamental design for an automotive fluid servicing cabinet, as shown and described.

DESCRIPTION

FIG. 1 is a forward left perspective view illustrating my new design;

FIG. 2 is a front view, in enlarged scale, thereof;

FIG. 3 is a left hand end view, in enlarged scale, thereof;

FIG. 4 is a top view, in enlarged scale, thereof;

FIG. 5 is a right hand end view, in enlarged scale, thereof;

FIG. 6 is a rear view, in enlarged scale, thereof; and,

FIG. 7 is a bottom view, in enlarged scale, thereof.

The broken line disclosure in FIG. 1 is for illustrative purposes only and forms no part of the claimed design.
